KERF-CUTTING MACHINE

Frank A. Lindgren, Western Springs, Ill., assignor
to Goodman Manufacturing Company, Chicago,
Ill., a corporation of Illinois

Application December 30, 1940, Serial No. 372,304

10 Claims.

(Cl. 262—30)

This invention relates to improvements in kerf-cutting machines of the room and pillar type.

One of the objects of my invention is to provide a new and improved kerf-cutting machine of a simplified construction including a compact fluid operated drive to the feed mechanism, arranged with a view towards simplicity and ease in operation and control.

Another object of my invention is to provide a novel and simplified form of retarding means for maintaining the machine in the proper relation with respect to the coal face, during the cutting operation, to take the place of the usual separate tail rope and retarding drum, which includes a ground engaging member mounted on the retreating side of the machine and selectively operable to engage the ground and to provide a retarding effect on the rear end of the machine.

A more specific object of my invention is to provide a new form of retarding device for maintaining the machine in the proper relation with respect to the coal face during cutting, including a rotatable traction wheel adjustable for engagement with the ground and adjustable longitudinally of the machine, to take care of varying conditions of cutting, together with means for retarding rotation of said traction wheel.

Other objects of my invention will appear from time to time as the following specification proceeds and with reference to the accompanying drawings wherein:

Figure 1 is a fragmentary plan view of a kerf-cutting machine constructed in accordance with my invention with certain parts broken away and certain other parts shown in horizontal section;

Figure 2 is a view in side elevation of the machine shown in Figure 1, with certain parts broken away and certain other parts shown in longitudinal section;

Figure 3 is a fragmentary longitudinal sectional view of the machine, taken substantially along line 3—3 of Figure 1;

Figure 4 is a fragmentary longitudinal sectional view of the machine, taken substantially along line 4—4 of Figure 1;

Figure 5 is an enlarged transverse sectional view taken substantially along line 5—5 of Figure 1;

Figure 6 is an enlarged detail view showing certain details of the drive to the feed drum in longitudinal section;

Figure 7 is an enlarged detail view showing certain details of the retarding device;

Figure 8 is a diagrammatic view illustrating the fluid circuit; and

Figure 9 is a diagrammatic view showing the machine cutting across a coal face and illustrating certain positions thereof during cutting with varying lengths of cutter bars.

In the drawings, the embodiment of my invention illustrated includes an underframe formed from a bottom plate 10, herein shown as being in two sections and extending the length of the machine and having upturned side walls 11, 11, forming a support for a motor 12 at the front thereof and for a frame and gear housing 13 at the rear thereof. Said housing is adapted to house and form a bearing supporting means for the drive from said motor to the feed gearing and cutter chain drive mechanism, as will hereinafter be more fully described as this specification proceeds.

A cutter bar generally indicated by reference character 16 is mounted on the underside of the motor 12 and gear housing 13, and projects forwardly from the forward end of said motor. Said cutter bar is of a usual construction having a channelled guide extending along the periphery thereof, for guiding a cutter chain 17 for orbital movement thereabout in a closed path. The arrangement of the side walls 11, 11 and the mounting of the cutter bar on the underside of the motor casing are such that the cutter chain moves in the space between the top of said bottom plate and the bottom of said motor and gear housing to a point adjacent the rear end of said underframe, for discharging cuttings from the rear end of the machine.

A cutter chain drive sprocket 19 meshes with the cutter chain 17 and forms a drive means therefor. Said sprocket is keyed on the lower end of a vertical shaft 20, journaled in the frame and gear housing 13. Said vertical shaft is disposed adjacent the rear end of said gear housing and is journaled in said gear housing on spaced bearings 21, 21. One of said bearings is disposed just above the hub of the sprocket 19 and the other is disposed at the upper end of said vertical shaft and is mounted in a bearing support portion 22 of the frame 13. A hub 23 of a bevel gear 24 is journaled on said vertical shaft and has a clutch member 25 splined thereon. The jaws of said clutch member are adapted to engage jaws 26, 26, formed in a clutch member 27 secured to said vertical shaft, for selectively driving said shaft and the sprocket 19 from said bevel gear.

The drive from the motor 12 to the bevel gear 24 includes an armature pinion 29, which meshes with and drives a spur gear 30, on the forward end of a longitudinal shaft 31. A bevel pinion 32 is keyed on said longitudinal shaft and meshes with and drives the bevel gear 24.

A truck driving socket 33 is driven from the shaft 31 by means of an aligned shaft 34 and a flexible coupling 38. The truck is driven from said socket by means of a detachable coupling pin (not shown). The truck and truck drive are no part of my present invention so are not herein shown or described.

A winding drum 35, having a flexible cable 36 adapted to be wound thereon, is provided to sump the cutter bar endwise into the coal face, and to feed said cutter bar laterally across the coal face when sumped therein. Said winding drum, as herein shown, is freely mounted on one side of the frame and gear housing 13 on a transversely disposed stub shaft 37, mounted in said frame and gear housing (see Figure 1).

Referring now in particular to the novel and compact form of fluid drive from the motor 12 to the winding drum 35, the armature pinion 29 meshes with and drives a spur gear 39 on a longitudinal shaft 40. Said longitudinal shaft forms a drive shaft for a pair of tandem pumps 41 and 42, adapted to supply fluid under pressure to a fluid motor 45. Said pumps may be of any well known type, but are herein shown as being rotary sliding vane types of pumps of a well known construction. Each of said pumps is of a different capacity so that one of said pumps may drive the fluid motor 45 and winding drum 35 at one speed and the other pump may drive said fluid motor and winding drum at a lower feeding speed. Pressure pipes 43, 43 lead from said pumps to a valve 44, herein shown as being a simple form of 4-way valve, having connection with the pressure side of the fluid motor 45, for driving said motor.

The fluid motor 45 may be of an ordinary rotary type well known to those skilled in the art, so will not herein be shown in detail. A longitudinally extending shaft 47 is journaled in said gear housing, coaxially with the drive shaft of said fluid motor, and has connection with said drive shaft through a coupling generally indicated by reference character 48. Said longitudinal shaft has a worm 49 mounted thereon, which meshes with and drives a worm gear 50 on a transverse shaft 51. Said transverse shaft is suitably journaled in said gear housing, and as herein shown has a gear 53 formed integral with the outer end thereof. Said gear forms a drive means for a planetary geared reduction device 54 and meshes with planetary pinions 55, 55 mounted on stub shafts 56, 56. Said stub shafts are mounted in a cage 57, of said planetary. Said planetary pinions mesh with an internal gear 59 forming a reaction member for said planetary and secured to a frame portion 60 of said gear housing. The cage 57 is herein shown as having a sleeve 61 formed integral therewith and journaled in said gear housing. A spur pinion 63 is formed integrally with said sleeve and meshes with an internal gear 64 rotatably mounted within a flanged portion 65 of the winding drum 35. A driving pin 66 is mounted in a webbed portion 67 of said winding drum and is adapted to have engagement with either one of a plurality of apertures 68, 68 formed in the web of said internal gear, and

forms a means for selectively connecting said internal gear with said winding drum.

The fluid connections from the pumps 41 and 42 to the fluid motor 45 through the valve 44 are illustrated in Figure 8, and are so arranged that when said valve is in position to connect one of said fluid pumps to the fluid motor 45, the pressure side of the other fluid pump will be connected to a fluid storage tank 69, and vice versa. Thus, the fluid motor 45 may be driven from one of said fluid pumps at a relatively high rate of speed, for driving the winding drum at a high positioning speed, for transporting the machine about the mine on its own bottom and positioning it for cutting in the coal face, or said fluid motor may be driven through the other fluid pump, for driving said winding drum at a low feeding speed, for feeding the machine across the coal face by means of the flexible cable 36.

Referring now to the novel form of retarder device, for maintaining the machine in substantially perpendicular relation with respect to the coal face during cutting across a coal face, a depressible retarding device 70 is provided. Said retarding device is herein shown as being a traction wheel adapted to be engaged by a friction band 71, for retarding rotation thereof. Said traction wheel is freely mounted on a horizontal shaft 74, which is mounted at its ends in a swiveled supporting frame 75 (see Figures 1, 2 and 7). Said swiveled supporting frame is pivotally mounted on the lower end of a piston rod 76, for movement about a vertical axis, and is held from vertical displacement with respect thereto by means of a nut 77, threaded on the lower end of said piston rod and engaging the underside of said vertically extending supporting frame.

The piston rod 76 depends from a piston 78, mounted in a vertically extending cylinder 80. Said cylinder is mounted in a guide 84, extending along the gear housing 13, for longitudinal adjustment with respect to the machine. A guide plate 85 is herein shown as being formed integral with the cylinder 80 and as extending laterally beyond the sides of said cylinder and forwardly and rearwardly therefrom. Said guide plate slidably engages the guide 84 and is held in engagement therewith by means of retaining gibs 86, 86.

The guide plate 85 is provided with a depending wall portion 87 extending around the traction wheel 70 and frame 75, and having an arcuate outer face 88 extending outwardly beyond the retreating side of the frame 13. Said wall portion engages an outer curved portion 89 of the frame 75, to form a curved guide therefor during pivotal movement of said frame and the traction wheel 70. Said swiveled mounting for said traction wheel thus permits said traction wheel to conform to the path of the mining machine as it is cutting across a coal face.

A threaded shaft 90 is provided to adjustably move the traction wheel 70 longitudinally of the frame 13, to adjust said wheel to place the required drag on the machine during cutting across the coal face (see Figure 2). As herein shown, said shaft has threaded engagement with a boss 91, projecting upwardly from the rear end of the guide plate 85 and journaled in a rear wall portion 92 of the frame 13. Said shaft has a squared outer end 93, adapted to be engaged by a suitable hand crank (not shown), for rotatably turning said shaft and slidably moving the guide

plate 85 and cylinder 80 in the guide 84, in an obvious manner.

The friction band 71 has a plurality of lugs 94, 94, projecting from opposite sides thereof. One of said lugs is adapted to engage a lug 96 in a rear wall 97 of the frame 75, and the other of said lugs is adapted to engage a lug 98 projecting inwardly from the outwardly curved wall 89 of said frame. A threaded rod 99 has pivotal connection with an inner end of said friction band and extends through a lug 100, secured to the opposite end of said friction band. A hand wheel 101 is threaded on the end of said rod and abuts a collar 102 encircling said rod and abutting the outer end of the lug 100. The collar 102 is mounted in an apertured portion of the wall 89 and extends through a longitudinally slotted portion 103 formed in the curved wall portion 88.

Fluid under pressure may be supplied by either of the pumps 41 or 42 to the head end of the cylinder 80, to depress the piston 79 in said cylinder and engage the traction wheel 70 with the mine floor. As herein shown, a pipe 105 leads from the valve 44 to a valve 106, which is herein preferably shown as being a 4-way valve. A flexible pipe or conduit 107 leads from said valve to the head end of said cylinder, for moving said piston in a downward direction. A flexible pipe or conduit 108 leads from said valve to the piston rod end of said cylinder, for elevating said traction wheel. A discharge pipe 109 leads from said valve to the tank 69. The valve 106 is so arranged that when in one position, fluid will be supplied to the head end of the cylinder 80, and exhausted from the piston rod end thereof through the discharge pipe 109, and when in another position fluid will be supplied to the opposite end of said cylinder and exhausted from the head end thereof, through the discharge pipe 109. When it is desired to hold pressure in said cylinder, to hold said piston and retarding device in the desired position of adjustment, said valve 106 is turned to an intermediate position, to close the ports leading to the pipes 107 and 108.

Referring now in particular to Figure 9, illustrating the use and operation of the retarding device, when the average machine is cutting across the coal face as indicated at "A," the cutting force on the advance side of the cutter bar in many cases is substantially equal to the frictional resistance of the rear end of the machine against the ground, especially when this cutter bar is relatively short. In cases like this, the friction band 71 may be disengaged from the retarding wheel 70, to permit free rotation thereof. When, however, a hard spot is encountered in the coal, increasing the resistance against the advance side of the cutter bar, the tendency will be for the machine frame to travel ahead of the cutter bar. After the cutter chain has cut through this hard spot, the pressure on the advance side of the cutter bar will be relieved, but unless the frictional resistance of the machine against the ground is greater than the force exerted against the forward end of the cutter bar, the inclination of the machine with respect to the coal face will continue to increase during the remainder of the cutting operation, thus reducing the cutting effectiveness of the cutter bar, and in severe cutting conditions causing the entire cutter bar to withdraw from the coal face. In order to provide this frictional resistance and retard travel of the rear end of the machine, the friction band 71 may be applied to the retarding wheel 70, said wheel being in engagement with

the ground. The amount of pressure with which said friction band engages said wheel may be varied to the extent necessary to provide the desired degree of resistance in rotation of said wheel, and to maintain the machine substantially perpendicular to the coal face. Said wheel may also be moved longitudinally of the machine, to provide resistance against the ground at the required point.

The machine shown by broken lines at "B" in Figure 9 is provided with a longer cutter bar than normal. If the machine is cutting from right to left, it will normally assume a forwardly inclined position with respect to the coal face, and will have a tendency to continue to pivot in the same direction, even where the cutting is soft. In cases where the force exerted against the advance side of the cutter bar is so great that the retarding device will not prevent this forward tilting movement of the cutter bar when positioned as in "A" and "B," said retarding device may be moved rearwardly along the machine frame in the guide 84, as indicated by diagram "C" in Figure 9, to increase the retarding effect of the wheel 70 an amount sufficient to bring the machine and cutter bar to a normal or substantially perpendicular position with respect to the coal face.

The retarding device thus eliminates the training of a tail rope from the machine and the setting of a jack therefor, and is readily adaptable to varying conditions and degrees of cutting, thus facilitating the cutting operation.

If it is desired to tilt the machine about the advance side thereof, to prevent the cutter bar from rising in the coal face, during the cutting operation, fluid under pressure may be admitted to the head end of the cylinder 80 until the retarding wheel 70 raises the retreating side of the machine about the advance side thereof.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a kerf-cutting machine, a winding drum having a flexible feeding member adapted to be wound thereon for feeding said kerf-cutting machine across a coal face, and means for retarding forward travel of the rear end of said kerf-cutting machine during cutting across a coal face including a rotatable retarding member adapted to have engagement with the ground, and means for restraining rotation of said retarding member.

2. In a kerf-cutting machine, a winding drum having a flexible feeding member adapted to be wound thereon, for feeding said kerf-cutting machine across a coal face, and means for maintaining said kerf-cutting machine in the proper relation with respect to the coal face during cutting across a coal face including a retarding member mounted on the retreating side of said kerf-cutting machine, for adjustable engagement with the ground and for adjustment longitudinally of said kerf-cutting machine and arranged to exert sufficient frictional resistance against the ground to retard travel of the rear end of the machine.

3. In a kerf-cutting machine, a winding drum having a flexible feeding member adapted to be wound thereon, for feeding said kerf-cutting machine across a coal face, and means for maintaining said kerf-cutting machine in the proper relation with respect to the coal face during cutting across a coal face including a retarding member slidably mounted on the retreating side of said kerf-cutting machine, for adjustable movement longitudinally thereof, said member being pivotally movable about a vertical axis and being depressible for engagement with the ground.

4. In a kerf-cutting machine, a winding drum having a flexible feeding member adapted to be wound thereon, for feeding said kerf-cutting machine across a coal face, and means for retarding forward travel of the rear end of said kerf-cutting machine during cutting across a coal face including a rotatable retarding member adapted to have engagement with the ground, means for restraining rotation of said retarding member, and other means for adjustably moving said retarding member longitudinally with respect to said machine, for varying the retarding effect thereof.

5. In a kerf-cutting machine, a winding drum having a flexible feeding member adapted to be wound thereon, for feeding said kerf-cutting machine across a coal face, and means for retarding forward travel of the rear end of said kerf-cutting machine during cutting across a coal face including a rotatable retarding wheel engageable with the ground and mounted for adjustable pivotal movement about a vertical axis.

6. In a kerf-cutting machine, a winding drum having a flexible feeding member adapted to be wound thereon, for feeding said kerf-cutting machine across a coal face, means for retarding forward travel of the rear end of said kerf-cutting machine during cutting across a coal face including a rotatable retarding wheel engageable with the ground and mounted for adjustable pivotal movement about a vertical axis, and means for restraining rotation of said retarding wheel, when in engagement with the ground.

7. In a kerf-cutting machine, a winding drum having a flexible feeding member adapted to be wound thereon, for feeding said kerf-cutting machine across a coal face, and means for retarding forward travel of the rear end of said kerf-

cutting machine during cutting across a coal face including a rotatable traction wheel having engagement with the ground and mounted for pivotal movement about a vertical axis, means for retarding rotation of said traction wheel, and means for adjustably moving said retarding wheel longitudinally with respect to said frame, to vary the retarding action thereof.

8. In a kerf-cutting machine, a frame, a winding drum mounted on said frame and having a flexible feeding member wound thereon for feeding said kerf-cutting machine across a coal face, and means for retarding forward travel of the rear end of said kerf-cutting machine during cutting across a coal face including a rotatable retarding wheel mounted at one side of the machine and having rotatable engagement with the ground and mounted for pivotal movement about a vertical axis, means for adjustably moving said retarding wheel longitudinally with respect to said frame to vary the retarding action thereof, other means for retarding rotation of said wheel, and means for adjustably moving said retarding wheel in a vertical direction to engage said wheel with the ground with varying degrees of pressure and to tilt said kerf-cutting machine about the side thereof opposite from said retarding wheel.

9. In a kerf-cutting machine, a winding drum having a flexible feeding member adapted to be wound thereon, for feeding said kerf-cutting machine across a coal face, and means for maintaining said kerf-cutting machine substantially perpendicular to the coal face, during cutting across a coal face, including a rotatable retarding member engageable with the ground, and control means for said retarding member, for varying the retarding action thereof.

10. In a kerf-cutting machine, a winding drum having a flexible feeding member adapted to be wound thereon, for feeding said kerf-cutting machine across a coal face, and means for maintaining said kerf-cutting machine substantially perpendicular to the coal face, during cutting across a coal face, including a rotatable retarding member, means for moving said retarding member vertically for engaging said retarding member with the ground, and a manually controllable friction member engageable with said retarding member, for varying the retarding action thereof.

FRANK A. LINDGREN.
